(57) **CLAIM**

We claim the ornamental design for a measuring container with lid, as shown and described.

DESCRIPTION

FIG. 1 is a side elevation view of a measuring container with lid of the present invention, the opposite side being a mirror image thereof.

FIG. 2 is a front elevation view of the measuring container with lid taken from the left side of FIG. 1.

FIG. 3 is a back elevation view of the measuring container with lid taken from the right side of FIG. 1.

FIG. 4 is a top plan view of the measuring container with lid shown in the previous Figures.

FIG. 5 is a bottom plan view of the measuring container with lid shown in the previous Figures; and,

FIG. 6 is a perspective view of the measuring container with lid shown in the previous Figures.
